UNITED STATES PATENT OFFICE.

EMERY J. WILSON, OF CLEVELAND, OHIO.

ROTARY SPEED INDICATOR.

1,416,082.

Specification of Letters Patent. Patented May 16, 1922.

Application filed May 29, 1917. Serial No. 171,725.

To all whom it may concern:

Be it known that I, EMERY J. WILSON, citizen of United States, residing at Cleveland, in the county of Cuyahoga and State 5 of Ohio, have invented certain new and useful Improvements in Rotary Speed Indicators, of which the following is a specification.

This invention relates to rotary speed indicators in which the speed of rotation is 10 indicated by the action of centrifugal force of a liquid contained in a rotatable receptacle and it consists of a new device of new form and construction to which may be applied exact mathematical formulæ based on 15 the laws of centrifugal force of liquids. The invention further embodies features which enable the vital proportions of the construction on which such calculations are based to be attained with exactness and ease, so that, 20 in manufacturing, all instruments are correctly and continuously calibrated throughout their entire range of speed. The present invention is a carrying forward of the general principles presented in my companion 25 application filed December 21, 1916, Serial No. 138,212. The basis of the principles presented in the earlier application is found in the fact that while a liquid mass subjected to centrifugal action naturally 30 produces shifting of the vertex of the parabola through distances which are not proportional to the speed of rotation, it is possible to set up conditions wherein this shift of the vertex of the parabola takes place 35 through distances which are proportional to the speed of rotation of the liquid mass, this result being brought about by setting up forced positions of liquid mass equilibrium in place of the natural positions of mass 40 equilibrium. Such forced positions of equilibrium can be produced by employing a compensating face as a wall of the chamber within which one of the free liquid surfaces of the liquid mass travels during the mass 45 displacing action set up by the changes in speed of rotation, such face being traversed by the free liquid surface during travel of the surface.

The compensating face has a cross sectional contour of mathematically derived 50 characteristic, the contour line being preferably produced by the use of certain formulæ which are used in developing the contour line of the face. The general formulæ underlying the type of apparatus of which the 55 earlier application is a disclosure of one em-

bodiment, are set forth in detail in the said earlier application, and are therefore not repeated herein. The particular embodiment of the earlier application, however, has this 60 compensating face located as a wall of the inner chamber of the instrument—the chamber through which the axis of rotation extends—so that where this surface is located at a different point, certain of the formulæ 65 employed are varied in order to meet the changed conditions.

In the present invention this compensating face forms a wall of the outer chamber of the instrument, the free liquid surface of 70 the inner chamber remaining as the indicating surface—the surface which controls the change in indications in presence of speed 75 changes—compensation being provided within the outer chamber.

The essential elements of this invention comprise a rotatable receptacle having an outer or discharge chamber in constant liquid communication with the inner or fixed central chamber about which the receptacle 80 rotates, and indicating means for registering the change of level of the liquid in the central chamber due to centrifugal action. A leading feature of the invention is the novel form of discharge chamber used to effect a 85 desired relation between the speed of rotation and said change of level of the liquid in the central tube. In instruments of this type, prior to said earlier invention, the liquid surface in the axial chamber descends 90 through distances which are not proportional to the speed of rotation, necessitating the use either of a non-uniformly graduated scale or of various devices in the register 95 operating mechanism such as cams, variable pitch spirals, etc., to rectify the scale. This present invention provides an exact mathematical derivation of the shape of the discharge chamber which will cause the said liquid surface in the central chamber to descend through equal distances for uniform 100 changes of speed of rotation throughout a comparatively large range of speed. Other features of the invention relate to details of construction which have been found essential 105 to the efficient operation of the device and its ease of manufacture.

My preferred form of construction comprises a fixed axial chamber, a receptacle 110 adapted to rotate about said axial chamber, said receptacle having an annular discharge chamber concentric with the axis and pas-

5 sages connecting the two said chambers; a scale member having a cylindrical graduated surface adapted to be rotated about the axis of the receptacle by means of a float
10 5 supported upon a mercury column contained in the axial chamber, said float having both an axial movement controlled by the rise and fall of said mercury due to centrifugal action of the mercury, and a movement of rotation controlled by a helical groove formed in said fixed axial chamber; the rotary motion of the float being communicated to the scale member by means of a square spindle along which the float is free to slide.
15 10 15 A specific embodiment of my invention is illustrated in the accompanying drawings in which Figs. 1, 2 and 3 are front and side elevations and plan respectively of the device assembled; Figs. 4, 5, 6 and 7 are sections on the lines X-X, a-a, b-b and c-c, respectively, of Fig. 8; Fig. 9 is an enlarged view of the outline of the discharge chamber showing the generating curve for the calibration surface; Figs. 10, 11 and 12 20 25 30 show developed diagrammatic views of the helix and the scale respectively to illustrate certain features in the operation of the device at low speeds; Fig. 13 is a diagrammatic view showing, in detail, the movement of the vortexes and the confining surfaces traversed by them, and Figs. 14 and 15 are diagrammatic views used in deriving the mathematical formulae.
35 40 45 50 55 60 65 70 75 80 85 90 95 100 105 110 115 120 125 130 In the figures 1 indicates a face plate supporting the frame 2 which in turn supports the rotating unit comprising a body 3 and cap 4. A tubular member 5, held fixed at its upper end in the frame 2 by nuts 6 and 7, serves as a journal for the cap bearing 8 and extends downward into the body of the receptacle thereby forming a fixed axial chamber 9 about which the entire receptacle is free to rotate. The lower end of said tube 5 is provided with a plug 10 which has passages 11 uniting the chamber 9 with the clearance space 12 surrounding the lower part of the tube. A discharge chamber 13 is formed between the body 3 and cap 4, and inclined passages 14 join the chamber 13 and clearance space 12 so that there is a constant liquid communication between the axial chamber 9 and the discharge chamber 13. The lower end of the body 3 is provided with an extension forming a step bearing 15, a journal 16, and carries a cross pin 17 at its lower end for rotating the receptacle as, for example, by means of a flexible shaft (not shown). A bearing 18, supported by frame 2, receives the journal 16 and is provided with a screw thread 19 for attaching the flexible shaft coupling customarily used in automobile practice. Another screw thread 20 carried by the body 3 serves as a worm for driving the distance recording number wheels 21 shown enclosed in a suitable cas-

ing 22. Since this mechanism is of common use and does not concern this invention, except as it may enter the combination, further detail and description are not deemed necessary. The dial 23 is supported upon and rotated by the spindle 24 having an upper journal 25 in plug 26 which fits tight in the tube 5 and a pivot bearing 27 in plug 10 at the lower end of the tube. The spindle 24 is of square section and carries the float 28 which is free to slide along but not to rotate upon the spindle, said float being provided with a pin 29 which works in a spiral groove 30 formed in the fixed tube 5, so that as the float moves up and down along the spindle, 70 75 80 85 90 95 100 the float, spindle and dial are all rotated by the pin following the groove. The dial 23 is graduated upon its outer cylindrical surface and the numbers 31 on the dial indicate miles per hour as is customary in automobile practice. The face plate 1 has an opening through which a portion of the dial protrudes thereby exposing to view in the front elevation enough of the graduations and numbers to be easily read as the scale moves under the fixed index point 32.

In reducing this invention to practice certain details of construction have been found very essential to its efficient and accurate operation:—There must be no liquid communication between the central chamber 9 and the clearance space 12 except at a point 33 located centrally at the lower end of the tube 5, because the height of a liquid in the central chamber is calculated at the apex of the continued parabolic surface of the liquid in the discharge chamber as indicated in Fig. 9. If the outlet 33 were located off center the height of liquid in the central chamber would be at a level above the said apex, 105 this level being determined by the point at which a vertical line through the outlet would intersect the said parabolic curve. It is to be noted that since the liquid in the central chamber does not rotate, its top free surface always remains a plane surface neglecting of course the effect of capillarity. For this reason the passages 11 are shown inclined, and a tubular casing 34 is provided which fits snugly around the fixed tube 5 110 and covers up the helical groove which is cut clear through the wall of the tube 5. A circular groove 35 of considerable depth is provided in the top surface of the body 3, which surface forms the bottom surface of the discharge chamber. This groove serves as a recess connecting the upper ends of the inclined passages 14 below the level X-X of the mercury when the instrument is at rest, and enables the mercury to rise and fall uniformly around the entire periphery 36 of the discharge chamber when the instrument is revolving at slow speeds. The introduction of a partition 37, held fast in the clearance space 12 at the lower end of tube 5, and 130

another partition 38, shown in Fig. 4, in the discharge chamber 13, serves to enforce and sustain the rotation of the mercury in conformity with the receptacle, and makes the device more positive in action. The lower part of the float 28 is reduced in diameter and made slightly conical producing a ledge 39 to which the float normally sinks in the mercury due to its own weight, and permitting the float to settle easily to this predetermined level. I find that if the float is made the same diameter all the way down it does not tend to sink to the same point under all working conditions, particularly so if there is a small clearance space between it and the tube 5. The top end of the float is made conical to prevent drops of mercury remaining upon it when, for example, the instrument is restored to its upright position after having been inverted.

The operation of the device is as follows:—When the receptacle is not rotating the axial chamber 9, clearance space 12, inclined passages 14 and circular groove 35 are filled with mercury to the level X—X; the float 28 is raised to its highest or initial position as shown in Fig. 8, and the zero on the scale is opposite the index point 32 as shown in Fig. 1. When the receptacle is rotated at a given speed the mercury descends a certain distance H in the central chamber 9, thereby permitting the float to fall to the position 28' and at the same time to be rotated through a certain angle by the pin 35 moving in the groove 30. This rotation is communicated to the dial 23 and the amount of rotation is indicated on the scale opposite the index point 32. The mercury flows from chamber 9 into the discharge chamber 13 where its free surface assumes a new position of equilibrium as shown at 40, due to the combined action of centrifugal force and gravity. The laws governing this action are known and definite, and it is possible to determine from them the exact form of a calibrating surface 41, in this discharge chamber which will cause the central mercury column to drop through distances which are directly proportional to the speed of rotation. In Fig. 9 two positions of equilibrium P_0 and P_1 are shown corresponding to a small change in the speed and the given assumed values of $H = H_0$ and $H = H_1$. Since the volume of mercury flowing from the central chamber must equal the volume which enters the discharge chamber we have:—

$(H_1 - H_0)$ times the net area of central chamber—the volume bounded by the four surfaces P_0 , P_1 , the base line X—X, and the calibration surface 41.

By applying the theory of limits to the above equation an exact equation for the

generating curve of this calibration surface has been derived, giving the variable relation between the coordinates x and y of the curve. The equation shows that this calibration curve is tangent to the base line X—X at a point which is at an infinite distance from the axis of rotation Y—Y. Hence a uniformly graduated scale will not give the correct reading below a certain speed of rotation depending on the maximum radius R_M of the calibration surface which it is practical to use, unless the upper end of the helical groove is changed to a spiral groove of variable pitch. Referring to Figs. 10, 11 and 12, the straight line $h—o$ represents the upper end of the developed helical groove, the distances h_1 , h_2 , h_3 . . . , drawn to an enlarged scale, represent the drops of the central mercury column for equal increments of speed corresponding to 1 mile per hour scale division, these distances being variable down to a point M, as the mercury works up along the vertical surface 36 in the discharge chamber. Beyond the point M the distances h_{13} , h_{14} , h_{15} . . . become uniform since the mercury is then working over the calibration surface 41 as previously explained. Fig. 12 shows how the scale would have to be graduated to give correct readings if a continuous helical groove were used. The broken line in Fig. 10 shows the developed spiral groove of variable pitch which is required above the point M to give a uniformly graduated scale as shown in Fig. 11, at these low speeds.

As shown by Figure 9, the compensating face 41 becomes active in producing travel 100 of the indicating free liquid surface through equal distances for equal increments of speed, only after the instrument has reached a certain definite speed of rotation, the speeds below such minimum of the compensating 105 face range having their indications provided by the compensating means indicated diagrammatically in Fig. 10. The manner of developing the compensating means of Fig. 10 has heretofore been pointed out. For the 110 purpose of making clear the development of face 41, the following explanation and formulae are given, this being based on the disclosures found in Figures 13 to 15, these formulae being more or less a continuation of 115 formulae shown in the said earlier application.

In Figure 13, the face 41 is indicated as C, B indicating the opposing surface of the outer chamber; this surface being of a selected geometrical design shown as presenting a face which extends perpendicular to the axis of rotation of the instrument. As will be understood, the free liquid surface of the outer chamber traverses these two faces 125 concurrently, these faces forming walls of

fixed dimensions between which the liquid operating within the chamber is confined.

For purposes of illustration, two parabolic vortexes are indicated, representing different positions of equilibrium of the liquid mass, the line n_1 showing the vortex which represents the position of the free liquid surface at the time when the compensating face becomes active during the progressive increase in speed of rotation of the instrument, the line n_2 showing the vortex produced when the speed of rotation is increased to substantially the maximum of the instrument.

When the instrument is at rest the free liquid surfaces of both chambers will extend on substantially the plane of surface B, this being represented by the line u_0 . During the travel of the vertex of the parabola from point i_0 on the line u_0 to the point i_1 —the point where line n_1 intersects the axis of rotation—the free liquid surface of the outer chamber is operating within the outer chamber under the principles of the natural law of centrifugal forces, the compensation for this range of travel of the vertex being provided by the spiral groove formation. At all points, however, in the travel of the vertex of the parabola between the position i_1 and the position i_2 in Fig. 13, the compensating face C is active and the conditions of forced positions of mass equilibrium are set up.

The general operation, referring to Fig. 13, is as follows:

(1) As the speed increases from $n=0$ to $n=n_1$ —The upper limit of the vortex curve travels upward from u_0 to u_1 , along the cylindrical surface, radius R_o , of the discharge chamber; the lower limit of the vortex curve intersects the base surface B at l_1 ; and the indicating surface moves downward from i_0 to i_1 in the central tube. For this range of speed the indicating surface moves through distances which are directly proportional to the square of the speed of rotation.

(2) As the speed increases from $n=n_1$ to $n=n_2$ (maximum)—The upper limit of the vortex curve travels upward from u_1 to u_2 along the calibration surface C; the lower limit of the vortex curve travels inward from l_1 to l_2 along the base surface B; and the indicating surface moves downward from i_1 to i_2 in the central tube. For this range of speed the indicating surface moves through distances which are directly proportional to the speed of rotation due to the functioning of the calibration surface.

The following table indicates which proportions are assumed or are known constants, the variables indicated depending

upon the speed of rotation and these constants:

CONSTANTS.

The lower confining wall B of the discharge chamber is a plane surface perpendicular to the axis of rotation. The zero level of the liquid lies in this plane.

Given basic proportions.

l =uniform movement of float for one R. P. M. change of speed.

ρ =radius of net area of central column; i. e., if—

r =inside radius of tube 5.

a_1 =cross-sectional area of spindle.

a_2 =cross-sectional area of groove in tube.

Then

$$\rho = \sqrt{\frac{\pi r^2 + a_2 - a_1}{\pi}}$$

R_o =maximum radius of discharge chamber.

Derived constants.

c =.0000142 (source found in application Ser. No. 138,212.)

n_1 =speed (R. P. M.) at which uniform movement of float starts.

H_1 =length of non-uniform movement of float.

$$R_1^2 = R_o^2 + \rho^2 - \rho \sqrt{2R_o^2 + \rho^2}$$

R_1 =radius of point of intersection of vortexes and base surface B during

period when the outer edge of the vortex travels along the vertical wall having radius R_o ; this period is represented in Fig. 13 by distance u_0-u_1 .

This point serves to locate the wall face represented by $u_1-u_1^1$, in Fig. 13, this face being parabolic in form and conforms to the parabolic vortex n_1 shown in Fig. 13. During this period the lower edge of the vortex within the discharge chamber does not travel along the base surface B but simply intersects such surface at

the distance R_1 from the axis; the annular groove at the periphery of the discharge chamber and which lies below the zero level of the mercury may be of any desired width provided its inner wall does not come within the value of R_1 —it is made narrow to reduce the volume of mercury required.

VARIABLES.

 n =R. P. M. H =displacement of float from base line or zero level.5 R =horizontal coordinate of calibration curve. x =vertical coordinate of calibration curve.

10 The following general formulæ are used in plotting the calibration curve—the contour of compensating face 41—and for determining the position of the float at all speeds:

For calibration curve.

15
$$R^2 = \frac{\sqrt{4cl\rho^2n + l^2 + l}}{2cn}$$

$x = cR^2n^2 - ln$

$H = ln$

20 Limit: $-n_1 = \frac{l}{cR_1^2}$

For initial speeds.

25 $H = cn^2(R_o^2 + \rho^2 - \rho\sqrt{2R_o^2 + \rho^2}) = cn^2R_1^2$

The principles employed in deriving these formulæ are as follows:

30 (1) For initial speeds.—Referring to Fig. 14, since the volume of mercury in the dis-

charge chamber above the zero level is equal to the volume of the tube space which the index surface—the free liquid surface of the inner chamber—has swept through in moving from its highest or initial position to the 35 position corresponding to the speed n , the position of any vortex curve can be determined and the value of H can be expressed in terms of n and the known constants. 40(2) For calibration curve.—Referring to Fig. 15, since the increment of mercury volume dV flowing into the discharge chamber for a small change of speed dn , is equal to the known mercury volume $\pi\rho^2ldn$ 45 which flows from the central tube, we have $dV = \pi\rho^2ldn$. But dV can be expressed in terms of the known constants c and l , the speed n with its increment dn , and the variable coordinates R and x with their increments dR and dx , so that as dn approaches zero as its limit, the resulting equation gives the variable relation between R and x and the known constants. 50The specific derivation of the formulæ 55 for the initial speeds,—that portion of the shifting of the vertex represented by the distance H_1 in Fig. 13—is as follows where the conditions are such as are indicated in the diagram shown as Fig. 14. 60

$$Vabc = \pi\rho^2H \quad \dots \quad (1)$$

But

$$Vabc = Vadoc - Vadoba = Vadoc - (Vadvba - Vbovb)$$

$$= \pi R_o^2 x - \frac{\pi}{2} R_o^2 (H + x) + \frac{\pi}{2} R_1^2 H = \pi\rho^2 H$$

$$\therefore 2R_o^2 x - R_o^2 (H + x) + R_1^2 H = 2\rho^2 H \quad \dots \quad (2)$$

From the general equation of the parabolic vortex

$$H = cn^2R^2 \quad \dots \quad (3)$$

We have:—

$$H + x = cn^2R_o^2 \text{ or } x = cn^2R_o^2 - H \quad \dots \quad (4)$$

And

$$H = cn^2R_1^2 \text{ or } R_1^2 = \frac{H}{cn^2} \quad \dots \quad (5)$$

∴ from (2), (4) and (5)

$$2R_o^2(cn^2R_o^2 - H) - R_o^2cn^2R_o^2 + \frac{H^2}{cn^2} = 2\rho^2H$$

$$2R_o^4cn^2 - 2R_o^2H - R_o^4cn^2 + \frac{H^2}{cn^2} = 2\rho^2H$$

$$R_o^4c^2n^4 - 2(R_o^2 + \rho^2)cn^2H + H^2 = 0$$

$$H^2 - 2(R_o^2 + \rho^2)cn^2H + (R_o^2 + \rho^2)^2c^2n^4 = (R_o^2 + \rho^2)^2c^2n^4 - R_o^4c^2n^4$$

$$H - (R_o^2 + \rho^2)cn^2 = \sqrt{c^2n^4[(R_o^2 + \rho^2)^2 - R_o^4]}$$

$$= cn^2\sqrt{R_o^4 + 2R_o^2\rho^2 + \rho^4 - R_o^4}$$

$$= cn^2\rho\sqrt{2R_o^2 + \rho^2}$$

$$\therefore H = cn^2[R_o^2 + \rho^2 \pm \rho\sqrt{2R_o^2 + \rho^2}] \quad \dots \quad (6)$$

From (5) and (6)

$$R_1^2 = [R_o^2 + \rho^2 \pm \rho \sqrt{2R_o^2 + \rho^2}] \quad \dots \dots (7)$$

When $n = n_1$ $H = H_1 = ln_1$

5 $\therefore ln_1 = cn_1^2 R_1$

$$\therefore n_1 = \frac{l}{cR_1^2} \quad \dots \dots (8)$$

10 The specific derivation of the compensating face under conditions such as shown in Fig. 15 is as follows:

Then $dV = \pi \rho^2 l dn$ as dn approaches 0 as its limit.

$$dV = \frac{\pi}{2} [(R + dR)^2 [l(n - dn) + x] - (r + dr)^2 l(n - dn)] - \frac{\pi}{2} [R^2 (ln + x) - r^2 ln] = \pi \rho^2 l dn$$

$$(R + dR)^2 [l(n - dn) + x] - (r + dr)^2 l(n - dn) - R^2 (ln + x) + r^2 ln = 2 \rho^2 l dn \quad \dots \dots (I)$$

From the general equation of the parabolic vortex $cR^2 n^2 = H$ we have:—

$$c(R + dR)^2 (n - dn)^2 = l(n - dn) + x \quad \dots \dots (1)$$

$$cR^2 n^2 = ln + x \quad \dots \dots (2)$$

$$c(r + dr)^2 (n - dn)^2 = l(n - dn) \quad \dots \dots (3)$$

$$cr^2 n^2 = ln \quad \dots \dots (4)$$

Substituting in (I):— $c(R + dR)^4 (n - dn)^2 - \frac{l^2}{c} - cR^4 n^2 + \frac{l^2}{c} = 2 \rho^2 l dn \quad \dots \dots (II)$

From (1) and (2) $c(R + dR)^2 (n - dn)^2 = cR^2 n^2 - ldn$

$$(R + dR)^2 = \frac{cR^2 n^2 - ldn}{c(n - dn)^2} \quad \therefore (R + dR)^4 = \frac{c^2 R^4 n^4 - 2cR^2 n^2 dn + l^2 dn^2}{c^2 (n - dn)^4}$$

Substituting in (II):— $\frac{c^2 R^4 n^4 - 2cR^2 n^2 dn + l^2 dn^2}{c(n - dn)^2} - cR^4 n^2 = 2 \rho^2 l dn$

$$c^2 R^4 n^4 - 2cR^2 n^2 dn + l^2 dn^2 - c^2 R^4 n^2 (n - dn)^2 = 2c \rho^2 (n - dn)^2 dn$$

$$c^2 n^2 [n^2 - (n - dn)^2] R^4 - 2cR^2 n^2 dn = 2c \rho^2 (n - dn)^2 dn - l^2 dn^2$$

$$c^2 n^2 (2n - dn) R^4 - 2cR^2 n^2 = 2c \rho^2 (n - dn)^2 - l^2 dn$$

25 At the limit this becomes:— $(dn = 0)$

$$2c^2 n^3 R^4 - 2c \rho^2 n^2 R^2 = 2c \rho^2 n^2$$

$$cn R^4 - lR^2 = l \rho^2$$

30 $R^4 - \frac{l}{cn} R^2 + \left(\frac{l}{2cn}\right)^2 = \frac{l \rho^2}{cn} + \left(\frac{l}{2cn}\right)^2 = \frac{4l \rho^2 cn + l^2}{4c^2 n^2}$

$$R^2 - \frac{l}{2cn} = \frac{\sqrt{4c \rho^2 n + l^2}}{2cn}$$

35 $R^2 = \frac{\sqrt{4c \rho^2 n + l^2} + l}{2cn} \quad \dots \dots (III)$

From (2) $x = cR^2 n^2 - ln \quad \dots \dots (IV)$

From (III) and (IV)

40 $cR^6 x = l^2 \rho^2 (R^2 + \rho^2) \quad \dots \dots (V)$

As will be understood, it is possible through the use of the compensating means

The curves P_1 and P_0 represent the parabolic vortexes corresponding to the speeds n and $(n - dn)$ respectively, where dn is a 15 very small change of speed.

dV —volume of mercury flowing out of discharge chamber for a decrease of speed $= dn$. This volume is bounded by the parabolic surfaces P_1 and P_0 , the base surface B , 20 and the compensating or calibration surface C .

$\pi \rho^2 l dn$ —volume of mercury flowing into center chamber for decrease of speed $= dn$.

$$cR^2 n^2 = ln \quad \dots \dots (4)$$

for the initial speeds and the compensating face for the speeds within the range limits of the face, derived under the formulae above pointed out, to produce an indicator of this general type in which the indications are substantially uniformly spaced; and it will also be understood that it is possible, 50 because of these facts, to manufacture indicators under production conditions, since it is possible to produce the compensating face by the use of dies, etc., so that the product will be uniform.

From the above it will be understood that I have provided a speed indicator wherein a confined liquid mass is subjected to centrifugal action to produce characteristics of a vortex, wherein the carrier for the liquid 60 mass is formed to provide inner and outer chambers in permanent communication and

with each chamber having a free liquid surface of the mass, the free surfaces being in permanent connection through the body of the mass, and wherein the indications are

- 5 made responsive to the changes in position of the free liquid surface of the mass of the inner chamber, such indicator having means operative to establish definite positions of equilibrium of the mass at definite speeds
 10 of rotation in presence of mass increment flow produced by variations in speed, said means including a face of such outer chamber positioned to be traversed by the free liquid surface operating in such chamber, said face having a cross sectional contour of
 15 mathematically-derived characteristic such as to cause the volumetric displacement represented by the movement of the free liquid surface of the outer chamber in moving
 20 from one position of mass equilibrium to another to be equal for equal increments of speed.

Having described my invention I claim as new:

- 25 1. In a speed indicator, a rotatable liquid receptacle having an axial chamber, a discharge chamber, an annular groove in said discharge chamber, and one or more passages uniting the axial chamber with the groove, said passages entering the groove at points below the normal level of the liquid when the instrument is at rest.
 30 2. A speed indicator having inner and outer communicating chambers for receiving liquid, the outer chamber constituting a discharge chamber into which the liquid flows upon rotation, said discharge chamber having for its lower boundary a plane surface provided with a peripheral groove communicating with the outer portion of said discharge chamber and having its upper surface so related to the lower surface that both surfaces are traversed by the free liquid surface, the relation between the surfaces of
 40 said chambers being such that equal variations in speed throughout a given range produce equal variations in liquid level, and indicating means responsive to the liquid level.
 45 3. A speed indicator having inner and outer communicating chambers for receiving liquid, the outer chamber constituting a discharge chamber into which the liquid flows upon rotation as it leaves the surface of the inner chamber, said discharge chamber having for its lower boundary a plane surface provided with a peripheral groove communicating with the outer portion of said discharge chamber and having an upper surface

50 equal variations in speed throughout a given range produce equal variations in liquid level, and indicating means responsive to said liquid level.

55 4. A speed indicator having inner and outer communicating chambers for receiving liquid, the outer chamber constituting a discharge chamber into which the liquid flows upon rotation as it leaves the surface of the inner chamber, said discharge chamber having two surfaces traversed by the liquid upon rotation, some of the surfaces of said chambers being of assumed form and the remaining surface having a form calculated with reference to the form of the assumed surfaces in such manner that equal variations in speed throughout a given range produce equal variations in liquid level within the inner chamber and indicating means responsive to said liquid level.

60 5. A speed indicating device provided with wall portions forming inner and outer communicating chambers concentric to an axis of rotation and containing a liquid, the wall portions of the inner chamber being stationary, means for producing rotation of the wall portions of the outer chamber and of the liquid therein about said axis thereby causing flow of liquid to the outer chamber, said inner and outer chambers having their respective wall portions so shaped and related to each other as to produce uniform variations of level of the liquid in the inner chamber for uniform variations in speed of rotation, and indicating means responsive to said liquid level.

65 6. In speed indicators, wherein a confined liquid mass is subjected to centrifugal action to produce characteristics of a vortex, wherein the carrier for the liquid mass is formed to provide inner and outer chambers in permanent communication and with each chamber having a free liquid surface of the mass, the free surfaces being in permanent connection through the body of the mass, and wherein the indications are made responsive to the changes in position of the free liquid surface of the mass of the inner chamber,

70 means operative to establish definite positions of equilibrium of the mass at definite speeds of rotation in presence of mass increment flow produced by variations in speed, said means including a face of such outer chamber positioned to be traversed by the free liquid surface operating in such chamber, said face having a cross-sectional contour of mathematically-derived characteristic such as to cause the volumetric displacement represented by the movement of the free liquid surface of the outer chamber in moving

- 75 from one position of mass equilibrium to another to be equal for equal increments of speed.
 80 7. In speed indicators, wherein a confined liquid mass is subjected to centrifugal action to produce characteristics of a vortex, wherein the carrier for the liquid mass is formed to provide inner and outer chambers in permanent communication and with each chamber having a free liquid surface of the mass, the free surfaces being in permanent connection through the body of the mass, and wherein the indications are made responsive to the changes in position of the free liquid surface of the mass of the inner chamber,

85 means operative to establish definite positions of equilibrium of the mass at definite speeds of rotation in presence of mass increment flow produced by variations in speed, said means including a face of such outer chamber positioned to be traversed by the free liquid surface operating in such chamber, said face having a cross-sectional contour of mathematically-derived characteristic such as to cause the volumetric displacement represented by the movement of the free liquid surface of the outer chamber in moving from one position of mass equilibrium to another to be equal for equal increments of speed.

90 7. In speed indicators, wherein a confined liquid mass is subjected to centrifugal action to produce characteristics of a vortex, wherein the carrier for the liquid mass is formed to provide inner and outer chambers in permanent communication and with each chamber having a free liquid surface of the mass, the free surfaces being in permanent connection through the body of the mass, and wherein the indications are made responsive to the changes in position of the free liquid surface of the mass of the inner chamber,

liquid mass is subjected to centrifugal action to produce characteristics of a vortex, wherein the carrier for the liquid mass is formed to provide inner and outer chambers in permanent communication and with each chamber having a free liquid surface of the mass, the free surfaces being in permanent connection through the body of the mass, and wherein the indications are made responsive to the changes in position of the free liquid surface of the mass of the inner chamber, means operative to establish definite positions of equilibrium of the mass at definite speeds of rotation in presence of mass increment flow produced by variations in speed, said means including a pair of faces constituting wall portions of the outer chamber positioned to be concurrently traversed by the free liquid surface operating in such chamber, one of said faces being of selected geometrical design, the other of such faces having a cross-sectional contour of mathematically-derived characteristic such as to cause the volumetric displacement represented by the movement of the free liquid surface over both faces in moving from one position of mass equilibrium to another to be equal for equal increments of speed.

8. In speed indicators, wherein a confined liquid mass is subjected to centrifugal action to produce characteristics of a vortex, wherein the carrier for the liquid mass is formed to provide inner and outer chambers in permanent communication and with each chamber having a free liquid surface of the mass, the free surfaces being in permanent connection through the body of the mass, and wherein the indications are made responsive to the changes in position of the free liquid surface of the mass of the inner chamber, means operative to establish definite positions of equilibrium of the mass at definite speeds of rotation in presence of mass increment flow produced by variations in speed, said means including a pair of faces constituting wall portions of the outer chamber positioned to be concurrently traversed by the free liquid surface operating in such chamber, one of said faces being of selected geometrical design, a cross-section of the wall carrying such face presenting the face as extending substantially perpendicular to the axis of rotation, the other of such faces having a cross-sectional contour of mathematically-derived characteristic such as to cause the volumetric displacement represented by the movement of the free liquid surface over both faces in moving from one position of mass equilibrium to another to be equal for equal increments of speed.

9. In speed indicators, wherein a confined liquid mass is subjected to centrifugal action to produce characteristics of a vortex, wherein the carrier for the liquid mass is formed to

provide inner and outer chambers in permanent communication and with each chamber having a free liquid surface of the mass, the free surfaces being in permanent connection through the body of the mass, and wherein the indications are made responsive to the changes in position of the free liquid surface of the mass of the inner chamber, means operative to establish definite positions of equilibrium of the mass at definite speeds of rotation in presence of mass increment flow produced by variations in speed, said means including a pair of faces constituting wall portions of the outer chamber positioned to be concurrently traversed by the free liquid surface operating in such chamber, one of said faces being of selected geometrical design, a cross-section of the wall carrying such face presenting the face as extending substantially perpendicular to the axis of rotation, the other of such faces having a cross-sectional contour of mathematically-derived characteristic such as to cause the volumetric displacement represented by the movement of the free liquid surface over both faces in moving from one position of mass equilibrium to another to be equal for equal increments of speed, the direction of extension of the derived face within the limits of such equal displacement movement of the free liquid surface being such as to generally increase the distance between the faces in the direction of approach to the axis of rotation.

10. In speed indicators, wherein a confined liquid mass is subjected to centrifugal action to produce characteristics of a paraboloid in which the position of the vertex is variable in response to speed changes, and wherein the indications are responsive to the position changes of the vertex, a container for the liquid, said container being mounted to produce paraboloidal characteristics to the confined liquid, said container having communicating inner and outer chambers for the liquid, said chambers being formed and positioned to provide free liquid surfaces of the mass permanently connected by the body of the mass with the surfaces located respectively to operate within the two chambers and with the liquid surface of the inner chamber movable in correspondence with the vertex movement, said surfaces being variable in position through flow of the liquid responsive to speed changes, variation in position of the surfaces being such as to place them in definite relation to the lines of the changed paraboloidal conformation produced by the change in speed, said container including a derived face forming a wall of the outer chamber and active in controlling the amount of the liquid increment shifted in producing the surface variations, said face having a cross-sectional contour

such as to cause travel of the vertex of predetermined length in presence of a speed change increment of definite amount, the length of vertex travel for successive speed increments being of predetermined amounts for equal speed increments.

11. In speed indicators, wherein a confined liquid mass is subjected to centrifugal action to produce characteristics of a paraboloid 10 in which the position of the vertex is variable in response to speed changes, and wherein the indications are responsive to the position changes of the vertex, a container for the liquid, said container being mounted to 15 produce paraboloidal characteristics to the confined liquid, said container having communicating inner and outer chambers for the liquid, said chambers being formed and positioned to provide free liquid surfaces of the 20 mass permanently connected by the body of the mass with the liquid surfaces located respectively to operate within the two chambers and with the surface of the inner chamber movable in correspondence with the vertex movement, said surfaces being variable in 25 position through flow of the liquid responsive to speed changes, variation in position of the surfaces being such as to place them in definite relation to the lines of the changed 30 paraboloidal conformation produced by the change in speed, said container including a derived face forming a wall of the outer chamber and active in controlling the amount 35 of the liquid increment shifted in producing the surface variations, said face having a cross-sectional contour such as to cause travel of the vertex of predetermined length in presence of a speed change increment of 40 definite amount, the length of vertex travel for successive speed increments being of predetermined and equal amounts for equal speed increments within the limits of mass flow in which the free liquid surface traverses such derived face.

45 12. In speed indicators, wherein a liquid mass is subjected to centrifugal action to produce characteristics of a vortex, and wherein the indications are made responsive to the rise and fall changes in position of a free liquid surface with the changes resulting from mass increment flow between two permanently-communicating chambers of the liquid carrier, indicating mechanism, mechanism for translating the rise and fall 50 movements of such free surface into indicating-mechanism movement, means operative within definite speed limits for producing mass flow of equal increment amounts for equal increments of speed within such limits, 55 whereby free surface travel will be equal for equal speed increments within such limits, and means operative to compensate for mass flow of unequal increment amounts for equal

increments of speed without such speed limit range, such compensating means being effective to translate unequal lengths of travel of the free surface produced by speed increments of equal amounts into indicating mechanism movement in which the length of indicating mechanism movement is equal 65 for equal increments of speed.

13. An indicator as in claim 12, characterized in that the mass flow of unequal increment amount precedes that of equal increment amount in an ascending progression 70 of speed increments of equal amount, with the compensating means active solely below the minimum limits of the mass flow of equal increment amounts.

14. In speed indicators, wherein a liquid mass is subjected to centrifugal action, and wherein the carrier for the mass is formed to provide a pair of spaced-apart free liquid surfaces of and in permanent connection through the body of the mass, indicating 80 mechanism adapted to indicate variations in speed, and means rendered operative by the rise and fall of one of such free surfaces for producing equal travel of the indicating mechanism for equal increments of speed, 85 said means including mechanism for translating such rise and fall movements of the surface into movement of the indicating mechanism, means operative in the translating mechanism for compensating for unequal travel distances of such free surface for equal increments of speed during a portion of such rise and fall movement, and a carrier face operative to produce equal 90 travel distances of such surface for equal increments of speed during the remainder of such rise and fall movement of the surface.

15. An indicator as in claim 14 characterized in that the free liquid surfaces are respectively operative in inner and outer 100 chambers of the carrier, with the free surface which is active in the movement of the translating mechanism located and operative within the inner chamber and with the carrier face for producing the equal travel 105 movement of such free surface formed as a wall of the outer chamber and positioned to be traversed by the free surface of the outer chamber.

16. In speed indicators, wherein a liquid mass is subjected to centrifugal action, wherein the carrier for the mass is formed to provide a pair of spaced-apart free liquid surfaces of and in permanent connection through the body of the mass, and wherein the indications are responsive to the rise and fall movements of one of said free liquid surfaces, indicating mechanism, mechanism for translating surface rise and fall movement to the indicating mechanism, means 115 for producing rise and fall movements of

such free surface through equal distances for equal increments of speed within definite speed limits, and means operative in the translating mechanism for compensating for rise and fall movements of the surface through unequal distances for equal increments of speed without such limits whereby the indicating mechanism will indicate equal

increments of speed by equal lengths of travel of the mechanism indicator. 10
